STORAGE CONTAINER FOR CASSETTES OR THE LIKE

Robert F. Zottola, 225 Greenwich Ave.,
Greenwich, Conn. 06830

Filed Jan. 21, 1971, Ser. No. 108,667

Term of patent 14 years

Int. Cl. D3—02

U.S. Cl. D87—1

FIG. 1 is a perspective view of a storage container for cassettes or the like showing my new design with the cover closed;

FIG. 2 is a perspective view with the cover open; and
FIG. 3 is a rear elevational view with the cover closed.

I claim:

The ornamental design for a storage container for cassettes or the like, as shown.
